(57) **CLAIM**

The ornamental design for a baby bed, as shown and described herein.

DESCRIPTION

FIG. 1 is a top, right side perspective view of one embodiment of a baby bed according to the present invention; FIG. 2 is a front elevation view of the baby bed shown in FIG. 1;

FIG. 3 is a rear elevation view of the baby bed shown in FIG. 1;

FIG. 4 is a top plan view of the baby bed shown in FIG. 1; FIG. 5 is a bottom plan view of the baby bed shown in FIG. 1;

FIG. 6 is a right side elevation view of the baby bed shown in FIG. 1;

FIG. 7 is a left side elevation view of the baby bed shown in FIG. 1;

FIG. 8 is a top, right side perspective view of another embodiment of a baby bed according to the present invention;

FIG. 9 is a front elevation view of the baby bed shown in FIG. 8;

FIG. 10 is a rear elevation view of the baby bed shown in FIG. 8;

FIG. 11 is a top plan view of the baby bed shown in FIG. 8; FIG. 12 is a bottom plan view of the baby bed shown in FIG. 8;

FIG. 13 is a right side elevation view of the baby bed shown in FIG. 8; and,

FIG. 14 is a left side elevation view of the baby bed shown in FIG. 8.

The broken lines shown in the figures depict environmental subject matter only, and form no part of the claimed design.

1 Claim, 8 Drawing Sheets
